S. A. CARLSSON

IRRIGATION DOOR

Filed April 28, 1926

Inventor
Svante H. Carlsson

By Clarence A. O'Brien
Attorney

UNITED STATES PATENT OFFICE.

SVANTE A. CARLSSON, OF LETHBRIDGE, ALBERTA, CANADA.

IRRIGATION DOOR.

Application filed April 28, 1926. Serial No. 105,270.

My present invention has to do with the damming of irrigation ditches; and it contemplates the provision of a peculiar and advantageous irrigation door, susceptible of being readily moved from point to point and adapted to be expeditiously and easily placed in position to dam a ditch and being also adapted to be quickly and easily removed for transfer to and use at another point in the ditch; the door being adapted to effectively dam the ditch and to resist the pressure of water therein.

To the attainment of the foregoing, the invention consists in the improvement as hereinafter described and definitely claimed.

In the accompanying drawings, forming part of this specification:

Figure 1 is an elevation showing the irrigation door of my invention as the same appears precedent to the anchoring of the door in working position.

Figure 2 is a view like Figure 1 but showing the door as anchored or secured in position to dam the ditch.

Figure 3 is a vertical section taken in the plane indicated by the line 3—3 of Figure 2, looking toward the right.

Figure 4 is a top plan view of the irrigation door per se.

Similar numerals of reference designate corresponding parts in all of the views of the drawings.

I show in Figures 1 and 2 an irrigation ditch 1, and it will be understood from the foregoing that the function of my novel irrigation door is to dam the ditch and prevent the flow of water therethrough.

It is within the purview of my invention to form my novel door of any material or materials compatible with its purpose, though I prefer to have the door comprise a body plate 2 of appropriate sheet metal, and a reinforcing frame 3 applied and connected at 4 to one side of the body plate. I also prefer to have the side anchors 5 of the door integral with the said reinforcing frame 3, it being noted in this connection that each side anchor is formed by an extension of the top bar of the frame 3 and a pointed prong pendent from said extension, the pendent prong being spaced outwardly beyond the side edges of the body plate 2 so as to take secure hold in the ground designated by 6.

At an intermediate point in the height of

the door a reinforcing member 7 is interposed between the side portions of the reinforcing frame 3, the said reinforcing member 7 being apertured at 8 to snugly receive the vertical central anchor 9 of the door, the said anchor 9 being of general spike-form and being pointed at its lower end which is extended below the body plate, Figures 1 to 3. The anchor 9 is connected at 10 to the top bar of the reinforcing frame 3 and also to the body-plate 2 and is provided at its upper end with a flat head 11 upon which an operator's shoe may be disposed for the convenient downward thrusting of the anchor 9 and the door as a whole.

Each of the anchors 5 is provided with a foot piece 12 which is fixed to and surmounts the same so that each anchor may be depressed or forced downwardly into the ground to the extent shown by dotted lines in Figure 2 by pressure applied with the foot of an operator.

At this point I would have it understood that the vertical central anchor 9 is also connected to the reinforcing frame 3 and the body plate 2 at the point 13, Figures 1 and 2.

It will be apparent from the foregoing that by virtue of the construction of my novel irrigation door and the mode adopted for securing the said door against casual movement that the door will effectively resist the passage of water in an irrigating ditch.

In the practical use of my improvement, a door is placed in an irrigation ditch in the manner shown in Figure 2 and water is permitted to collect in the ditch at one side of the said door, and the operator then takes another door such as shown and places the same in the ditch several feet from the first-named door, and after the second door is placed in working position, the first named door is raised and water is permitted to pass slowly at first so as to avoid the imposition of unnecessary pressure against the second-named door, and so on; and in this latter connection it will be appreciated that the flat head 11 of the vertical central anchor 9 and the plates 12 above the side anchors render it feasible for an operator to quickly and conveniently raise my novel irrigating door to the extent desired.

I have explicitly described the construction and relative arrangement of the parts embraced in the present and preferred em-

2
bodiment of my invention in order to impart an exact understanding of the said embodiment in all of its details. I do not desire, however, to be understood as limiting myself to the precise construction disclosed, my invention being defined by my appended claim within the scope of which modifications may be made without affecting my invention or involving departure therefrom.

10 Having described my invention, what I claim and desire to secure by Letters Patent, is:—

15 The herein described irrigation door consisting essentially of a body plate, a continuous, one-piece reinforcing frame arranged at one side of and fixed to said body plate and having upper and lower and side bars, the upper bar terminating in lateral exten-

sions extending beyond the side edges of the body plate and provided at their outer ends 20 with pendent prongs constituting side anchors, superposed plates fixed on the upper bar of the frame and constituting horizontally disposed foot pieces, an apertured bar 25 interposed between and fixed to the side bars at intermediate points in the length of the latter, and a vertical central anchor connected with the body plate and with the upper and lower bars of the reinforcing frame and 30 extending through said apertured bar and also extending above and below the body plate and provided at its upper end with a head disposed in a horizontal plane above that of said foot pieces.

In testimony whereof I affix my signature.

SVANTE A. CARLSSON.
